UNITED STATES PATENT OFFICE.

BERT R. BENJAMIN, OF OAK PARK, ILLINOIS, ASSIGNOR TO INTERNATIONAL HARVESTER COMPANY OF NEW JERSEY, A CORPORATION OF NEW JERSEY.

SHOCKING-MACHINE.

1,222,717.

Specification of Letters Patent. Patented Apr. 17, 1917.

Application filed November 20, 1913. Serial No. 302,131.

To all whom it may concern:

Be it known that I, BERT R. BENJAMIN, a citizen of the United States, residing at Oak Park, in the county of Cook and State 5 of Illinois, have invented certain new and useful Improvements in Shocking Machines, of which the following is a full, clear, and exact specification.

My invention relates to shocking 10 machines.

In shocking machines of the swinging sheaf delivery member type, wherein a sheaf delivery member with tines thereon is used to convey the sheaves from a point 15 adjacent the binder deck to the sheaf receiving cradle of the shocker, it has been found that in certain cases in slippery grain, there is a tendency for the sheaf to shift longitudinally with respect to the sheaf 20 delivery member, resulting in the sheaves being positioned irregularly with respect to the end tines of the cradle so that, when the cradle is operated, the butts of the sheaves not being disposed in the same plane, a 25 shock of inferior standing quality is formed. It has further been found that in certain similar grain conditions there has been a tendency for the sheaf to drop downward from the sheaf delivery member after the 30 latter has passed over its center and before the sheaf is properly positioned over the cradle as the sheaf delivery member moves downward, with the result that the sheaves have been set irregularly in the cradle and 35 the standing qualities of the shock have been deleteriously affected.

My invention has for its object to hold the sheaf securely in position upon the sheaf delivery member as the latter moves 40 from sheaf receiving to sheaf delivery position, in such a manner that the sheaf will be held against longitudinal shifting with respect to the fork in the manner noted, and at the same time will be so held as to 45 be unable to leave the fork prematurely in the objectionable manner mentioned. I attain these objects by the provision of improved holding means for retaining the sheaf on the sheaf delivery member, comprising a tine having means thereon which, when the fork is driven into the sheaf, is likewise forced into the sheaf and, on account of its shape, acts to prevent both longitudinal movement of the sheaf with re-

spect to the sheaf delivery member, and premature separation of the sheaf therefrom. 55

In the accompanying drawings I have shown one form which my invention may assume in practice.

Figure 1 shows a top plan view of a sheaf 60 delivery member equipped with my improvement;

Fig. 2 shows a side elevation of the sheaf 65 delivery member in position beneath a sheaf; and

Fig. 3 is a sectional view of the sheaf 70 delivery member taken on line 3—3 of Fig. 2, the sheaf being shown in position on the latter and in section.

In the construction shown I have illustrated a sheaf delivery member 1 of the well-known Raney type, carried on a rotatable shaft 2 and attached thereto by suitable means 3. As in the usual Raney fork, a plurality of pairs of spaced parallel up- 75 standing tines 4 are provided upon the free end of the same, each pair of tines preferably being formed from the same piece of stock and the latter being disposed transversely of the fork body and attached thereto by any suitable means. Fitting over the free end of the fork 1 is also a tined member 5 having three upstanding tines 6 thereon disposed in a substantially triangular form, while intermediate the two sets of 80 tines 4 is a supplemental tine 7 secured directly upon the body of the fork, and on the shocker side of the inner tine 4 a second supplemental tine 8 is provided, similarly secured to the fork; the end tines serving 85 to penetrate the body of the sheaf near the butt, while the tines 7 and 8 penetrate the same on opposite sides of the band.

In the form of my improved construction illustrated herein this last tine 8 is so formed 90 as to coöperate with the other tines in holding the sheaf in an improved manner. In the embodiment of my invention shown herein this tine 8 is flattened between its ends, as shown in Fig. 3, in such a manner 95 that it widens gradually toward a point of maximum width a little over half way between its ends and toward its free end, and from that point tapers toward a point at its upper or free end; this tine being so positioned transversely with respect to the straws in the sheaf that the enlarged portion 100 thereon forms a projection or extension over

which the grain in a sheaf slides as the tine is moved into or out of the sheaf, yet which acts at the same time to form a substantial abutment preventing longitudinal movement 5 of the bound sheaf and, due to its increased width, also acts to resist momentarily a free downward slipping movement of the sheaf as the fork swings over to its inverted position.

10 Since the operation of a Raney shocker is well known and forms no part of the present invention *per se*, it seems unnecessary to describe the parts thereof in detail, it being sufficient to say that the fork 1 is swung 15 back and forth from the position shown in Fig. 2, wherein it lies under the binder deck of a harvester, to an inverted position, wherein it is over the shocker cradle, being turned by suitable mechanism (not shown)

20 and moving with the shaft 2, which is journaled in suitable bearings, likewise not shown. Obviously, when the fork moves upward from the position shown in Fig. 2, the tines thereon will be forced into the sheaf, 25 penetrating the latter and carrying the same backward in an arc to turn the sheaf while swinging about the shaft 2 as an axis. In this movement it is to be noted that the tine 8 forces back the straws and embeds itself 30 in the body of the sheaf at a point where the straws are tightly bound; *i. e.*, near the band, and that, due to its width, it also tends to obstruct and prevent longitudinal movement of the sheaf with respect to the 35 fork during the swinging movement, and toward the end of that movement, through its increased width, likewise acts to retain the sheaf upon the fork for the brief interval necessary to prevent the sheaf from sliding off downward prematurely as the fork swings through its quick downward stroke. Obviously, when the fork is driven backward, however; that is, from sheaf delivering 40 to sheaf receiving position, the tine 8 will then be readily withdrawn from the sheaf by the well-known quick return movement of the fork and the pull of gravity on the sheaf.

While I have in this application shown 50 one specific form which my invention may assume in practice, it is to be understood that I desire to cover in this application all of those modification thereof functioning to obtain the same results and consisting of 55 modifications thereof.

What I claim as my invention, and desire to secure by Letters Patent, is:

1. A shocking machine sheaf delivery member having thereon intermediate its ends 60 an upwardly extending tine, and means on said tine for spreading the inner stalks of a

sheaf on said delivery member, thereby resisting bodily movement of the sheaf with respect to the delivery member.

2. A shocking machine sheaf delivery 65 member having thereon an upwardly extending tine provided with a projecting edge disposed transversely with respect to the shank of said delivery member.

3. A shocking machine sheaf delivery 70 member having thereon an upwardly extending tine provided with oppositely extending projecting edges disposed transversely with respect to the shank of said delivery member. 75

4. A shocking machine sheaf delivery member having an upstanding flattened tine tapered toward its ends and disposed substantially transversely with respect to the shank of said sheaf delivery member. 80

5. A shocking machine sheaf delivery member having an upstanding tine provided with laterally extending edges intermediate its ends resisting bodily movement of a sheaf along or away from said sheaf delivery 85 member. 95

6. In combination, a sheaf delivery fork, and an upstanding flattened tine carried thereon and disposed transversely with respect thereto having tapered laterally extending enlarged portions on its sides spreading the straw in a sheaf near the band thereof as the sheaf is positioned thereon and resisting movement of the sheaf relative to said fork. 90

7. In combination, a sheaf delivery fork having longitudinally spaced pairs of upstanding tines thereon, the tines in each pair being themselves transversely spaced, and a supplemental tine engageable with a sheaf 100 on the opposite side of its band from one of said pairs of tines, said tine having means thereon resisting a longitudinal movement of the sheaf with respect to the delivery member. 105

8. In combination, a sheaf delivery fork having longitudinally disposed spaced pairs of upstanding tines therein, the tines in each pair being themselves transversely spaced, and a supplemental tine engageable with a sheaf on the opposite side of its band from one of said pairs of tines, said tine having means thereon for resisting a bodily movement of the sheaf along or away from said sheaf delivery fork. 110 115

In testimony whereof I affix my signature, in the presence of two witnesses.

BERT R. BENJAMIN.
